No. 14,604

FEB 5, 1884

UNITED STATES PATENT OFFICE.

JOSEPH HEAP, OF BURSLEM, COUNTY OF STAFFORD, ENGLAND, ASSIGNOR
TO MELLOR TAYLOR & CO., OF SAME PLACE.

DESIGN FOR A COVERED DISH.

SPECIFICATION forming part of Design No. 14,604, dated February 5, 1884.

Application filed December 1, 1883. Term of patent 3½ years.

To all whom it may concern:

Be it known that I, JOSEPH HEAP, of Burslem, in the county of Stafford, England, have invented a new and original Design for Covered Dishes, of which the following is a specification.

The nature of my design is fully shown in the accompanying photographic illustration.

The design includes both the cover *a* and body *b* of a covered dish. The cover has the general form of a truncated pyramid, having two longer and two shorter sides and slightly-rounded corners—that is to say, the base of the cover is an oblong rectangle with rounded corners. The sides are beveled inwardly and upwardly, and its top is flat, and is surmounted by a handle, *c*. The handle *c* forms a part of my design, and is composed of a central portion of medallion shape, and scroll-shaped offsets or braces extending from opposite edges of the central portion. The body of the dish is oblong, having two longer and two shorter straight sides in horizontal section, and rounded corners, having the same curvature as the corners of the cover. The base or lower portion of the body is inclined outwardly and upwardly to a shoulder, *e*, at or near the vertical center of the body, the vertical section of said portion presenting a convex curvature on its outer surface. Above the shoulder *e* the

body is carried upwardly, so as to present nearly vertical sides from said shoulder to the upper edge of the body, said sides being swelled outwardly at their lower portions. The ends of the body are provided with handles, which are like the handle on the cover. The bottom of the body has outwardly-beveled legs or offsets, on which the dish rests.

I claim—

1. The design for a covered dish, as described and shown.
2. In a design for a covered dish, the design for the dish-cover, as shown and described.
3. In a design for a covered dish, the design for the body having the outwardly-inclined base, the horizontal shoulder, and the approximately vertical upper portion, as shown and described.

4. In a design for a covered dish, the design for a cover or dish handle, as shown.

In testimony whereof I have signed my name to this specification, in the presence of two subscribing witnesses, this 14th day of November, 1883.

JOSEPH HEAP.
